ABSTRACT: An ignition assembly for lighting another device, such as a main burner (for example, the sampling burner of an atomic absorption spectrophotometer). An electrically heated igniter coil is placed at the edge of the gaseous (fuel and oxidant) stream of the auxiliary igniter burner, and a deflector causes a small part of this gaseous stream to contact the igniter coil. The igniter coil thus remains substantially outside the auxiliary flame thereby avoiding subjecting it to the intense heat of the full auxiliary flame. In operation, the coil is first energized to cause it to heat up, the auxiliary (igniter) burner is then supplied fuel, to cause the deflected part of the gaseous stream and therefore the whole stream to be ignited, which in turn lights the main device (e.g., sampling burner). The system may also be readily automated, so as to minimize manual operations by the user.

IGNITOR APPARATUS

GENERAL DESCRIPTION

This invention relates to an igniter for lighting another device, for example, a main burner. More particularly, the invention concerns an igniter of the type which itself is normally off (as contrasted to a continuously burning pilot light) which temporarily forms an ignition or pilot flame for igniting another device. Purely for purposes of concreteness and ease of explanation, it will be assumed that the device ultimately intended to be ignited is a main burner (and in particular one of the type utilized in analytical instruments, for example, for generating the sampling flame of an atomic absorption spectrophotometer).

In general the invention includes an igniter or auxiliary small burner from which a fuel and oxidant mixture issues in a generally jetlike stream, an electrical ignition coil or heating element positioned adjacent or at an edge of such stream, and a small deflecting plate for deflecting (a relatively small) part of the fuel and oxidant stream to at least part of the igniter coil. In operation the igniter coil is first heated, and then the fuel and oxidant stream initiated so that the small deflected part ignites, thereby igniting the entire stream of gaseous fuel and oxidant, while the ignition coil remains outside the main part of the igniter flame. The igniter flame may then be utilized to light a main device, such as a sampling burner of the premixed type utilized in atomic absorption spectroscopy. A major feature of the invention is the utilization of a small deflector plate in the gas stream from the igniter so as to insure that the heated igniter coil lights the stream, without being placed directly in the stream, thereby avoiding undue heating of the igniter coil from combustion of the gaseous fuel and oxidant flame. The use of such a deflector thus prolongs the useful life of the heating igniter coil.

One object of the invention is the provision of an apparatus for igniting another device (e.g., a main burner) by temporarily forming an igniting or auxiliary flame, while insuring that the means for igniting this auxiliary flame is not itself subject to substantial heating by the auxiliary flame once it has been lit.

A related object of the invention is the provision of such an ignition apparatus which insures long life of the (electrically heated) ignition coil, so as to insure that the ignition device may be utilized many times without risk of failure.

Other objects, features and advantages of the invention will become obvious to one skilled in the art upon reading the following detailed description of the invention as utilized in an exemplary embodiment for lighting a main burner (for example, the sampling burner of an atomic absorption spectrophotometer), which exemplary embodiment is shown in the accompanying drawings, in which:

FIG. 1 is a plan view of the auxiliary igniter nozzle or burner and the igniting element therefor;

FIG. 2 is a vertical section through the same elements shown in FIG. 1;

fig. 3 is a detail perspective view of the auxiliary igniter nozzle or burner itself; and

FIG. 4 is a partially schematic side view of an entire system incorporating an ignition device according to the invention.

DESCRIPTION OF EXEMPLARY IGNITION ASSEMBLY

In the FIGS. 1 and 2 detail plan and vertical section, respectively, through the parts of the igniter assembly proper, the igniter or auxiliary burner is shown at 10, while the ignition coil assembly therefor is shown at 12. The igniter assembly burner or nozzle 10 may consist of a single piece of, for example, round stainless steel stock, which has been drilled so as to include a horizontal inlet channel 14 for snugly receiving a tube 16 supplying the fuel in its main full-diameter portion 18. Although the exact dimensions are in general not critical, it may be noted that both FIGS. 1 and 2 are essentially to scale for an actual embodiment made and satisfactorily tested, and

the dimensions of this embodiment are hereinafter mentioned merely for exemplary purposes. Thus the internal diameter of fuel supply tube 16 may be 0.010 inches for use with acetylene gas under pressure of approximately 11 pounds per square inch and the internal diameter of channel 14 was 0.063 inches to snugly receive the similar outer diameter of such tubing. Main portion 18 narrows, as indicated by shoulder portion 20, to a (also generally round in cross section) nozzle portion 22 having a reduced external diameter. Tube 16 would normally be introduced in channel 14 up to a position 24 just beyond shoulder portion 20. Narrower portion 22 of the nozzle has a pair of bores or apertures extending radially therethrough, so as to form a series of four air-induction openings 26, 26', 28 and the hole (not shown) opposite hole 28, communicating with the extension 14' of channel 14. When the gaseous fuel is flowing (at a relatively rapid rate) through tube 16 and therefore channel extension 14', air will be induced through all four of the openings (26, 28, etc.) by Venturi action, much in the manner of a conventional Bunsen burner. Therefore when fuel is flowing through pipe 16, a relatively rapidly moving mixture of gaseous fuel and air will issue from the flared or trumpetlike opening 30 of the nozzle. Although the nozzle proper ends (as does of course the flaring portion) 30) at a right-hand edge or shoulder portion 32, generally triangular extensions 34 and 36 (compare FIGS. 2 and 3) are either integrally formed (as shown) or rigidly attached to the lateral edges of surface 32. These triangular extensions 34, 36 form a support for a small deflector plate 38. In particular deflector plate 38, preferably made of platinum, may consist of a main deflector portion 40 and a pair of short right-angle legs, one of which is seen at 42 in FIG. 2 (and both of which are indicated at 42, 44 in FIG. 1). The small deflecting portion 40 is therefore positioned in the lower part of the gaseous stream from flared opening 30 of the nozzle, so as to deflect a small part of this lower portion of the stream generally downwardly as seen in FIG. 2 (and indicated at 72, as later described).

Although the exact dimensions of the igniter assembly are not necessarily critical, the dimensions of an embodiment actually made and successfully tested are given, purely for exemplary purposes. The entire assembly 10 may be made from a single fifteen-sixteenths /16 (about 0.94) inch long piece of 303 stainless steel, originally in the form of three-eighth diameter round stock. The main body portion 18 is therefore of this diameter, but may carry threads as indicated at 19 on the exterior surface so as to be readily attachable to a convenient supporting plate or other structure 41, as by nuts 43,45. After extending for about 0.41 inches in length (horizontal dimensions of FIGS. 1 and 2), portion 18 narrows at shoulder 20 to the nozzle portion 22 which is also generally cylindrical (i.e., circular cross section) with an outer diameter of one-fourth (0.25) of an inch. The narrower nozzle portion 22 had a length of 0.34 inches from shoulder 20 to its front surface 32 with the center of the four holes (26, 28, etc.) being one-fourth (0.25) of an inch to the left of end surface 32. In the particular embodiment the diameter of these holes was three thirty-seconds (0.093) of an inch. The conical throat portion 30 was made by using a 45° countersink, which drilled front surface 32 to a sufficient depth to cause the larger (right-hand) diameter of the throat to reach a 0.16 inch diameter. Of the total distance of 0.25 inches from the center of the air-aspirating holes (e.g., 28) to the surface 32, a little less than 0.05 inch is counted by the half diameter of the hole, about 0.08 inch by the length of the channel 14', and about 0.12 inches by the generally conical flaring throat portion 30 of the nozzle. The generally triangular supporting bracket extensions 34, 36 had a length (i.e., the horizontal dimension in FIGS. 1 and 2) to their (extreme right-hand) lower point of about 0.19 inches. These triangular extensions are of course completely open at the top and bottom (see FIGS. 1 and 3) and have an internal space therebetween of approximately 0.18 inches in width (i.e., the vertical dimension in the top view of FIG. 2). Since their outer surfaces would normally conform to the tubular dimensions of the nozzle portion 22,

these external surfaces of extensions 34, 36 are curved as may best be seen in the elevational detail view of FIG. 3. The maximum thickness of extensions 34 and 36 is therefore one half of the outer diameter (0.25 inches), less the planar width therebetween (0.18) or one half of 0.070 inches, equal to 0.035 inches.

The attached deflector 38 may be made of a platinum ribbon of 0.005 inch thickness and a width of 0.040, which has been bent at right angles at both ends to form legs 42, 44 while leaving a central section 40 of 0.25 inch length (the vertical direction of FIG. 1 or the oblique direction of FIG. 3), not counting the thickness (0.005 inch) of each of the legs 42, 44. If the upper and lower very narrow portions of triangular extensions 34, 36 have been relieved for about 0.03 inches (as measured along surface 32) as indicated in FIG. 2, the lower part of deflector 38 will be very near (about 0.02 inches) from the extreme bottom of the front edge 35 of the oblique surfaces of extensions 34, 36. In other words, the bottom of the deflector 38 will be approximately 0.05 inches above the bottom of the point of nozzle 32. Since the deflecting part 40 of the deflector 38 is at a 45° angle, its effective vertical height as seen in FIG. 1 will be $0.040 \div \sqrt{2}$, or somewhat less than 0.03 inches. It will therefore directly intercept only about one-tenth of the width of the gas stream issuing from flat aperture 30. In this specific exemplary version, the deflector 38 would have its upper and lower surfaces about equally distant (namely, 0.05 inches each) from the centerline of nozzle portion 22 and its lower surface and would have an effective vertical extent of about 0.028 inches. Since more of the gas will issue near the centerline than near the edges of the threaded nozzle opening 30, the deflector actually directly encounters less than one-tenth of the total volume of gas, since it directly deflects a part of the stream that is half way between the centerline and the edge of the nozzle. However, the part of the gas stream which passes below the deflector 38 is also influenced by the deflected gas stream, which tends to follow the angled deflector surface because of the Coanda effect, so as to cause some of this gas to be deflected by the directly deflected gas generally downwardly in FIG. 2. The total fuel (e.g., acetylene) flow was about 140 cc. per minute through the exemplary igniter burner or nozzle 10.

An ignition coil 50 connected at its lower end 52 to a metallic pin 54 and at its upper end 56 to the upper surface 58 if a metal housing 60 is positioned below and to the right of deflector 38 as may best be seen in FIG. 2. An insulating plug or disc 62 centers pin 54 and therefore the lower end of coil 50 within the housing 60, which centering is also assisted by the connection of the upper end 56 of the coil in the manner illustrated. Electrical leads 64, 66 connected to a voltage source and switch (not shown in FIGS. 1 and 3) energize this assembly 12 (and in particular ignition coil 50) whenever the switch is closed. The electrical ignition assembly 12 may comprise a commercially available "glow plug" type of igniter, utilized for example as to initiate the combustion in model airplane engines. For example, a suitable glow plug is sold by the K & B Manufacturing Corporation, Downey, Calif., under the designation glow plug type KB-1L (K & B Drawing No. 0755, revision I dated Jan. 15, 1967). Obviously other glow plugs or even other types of similar ignition devices may be utilized instead. A bent bracket 51, rigidly attached to main supporting plate 41 may be utilized to hold the ignition coil assembly 12, as by providing threaded portion 53 on the upper part of housing 60 and a cooperating attaching nut 55.

The operation of the igniter assembly itself is relatively simple. Whenever the switch (not shown) closes a circuit through leads 64, 66, ignition coil 50 will start to heat up until it reaches a sufficient temperature to ignite the gases (for example acetylene mixed with the aspirated air) which is issuing from flared nozzle opening 30, and in particular that part thereof (72) which is deflected downwardly to the upper part of the ignition coil 50 by deflector 38. Preferably the ignition coil is allowed some time to heat up before the fuel is turned

on (by means hereinafter disclosed in exemplary form in FIG. 4) to tube 16 to avoid contamination of the atmosphere by unburned fuel. Once the deflected part at 72 of the gas stream has been ignited, the entire gas stream will of course be immediately kindled, resulting in a flame having the general shape indicated at 74 in FIG. 2. Flame 74 may then be utilized to ignite any other device 76, for example a main burner, as will be described in an exemplary complete system according to the invention immediately hereinafter. It should be noted that once the igniter flame 74 has been kindled, the ignition coil 50 is not subjected to the intense heat generated by this flame (or more accurately it is exposed only to the extreme edge of the deflected part of the flame). Additionally even the deflector 38 is not exposed to the hottest part of the flame, since it is both well off its center and is also sufficiently close to the nozzle so as to not be in the hottest part of the flame along its longitudinal (i.e., horizontal in FIG. 2) portion. A comparison of FIGS. 1 and 2 will show the relative positioning of various parts of the auxiliary burner or nozzle 10 and igniter or heater 12 in the exemplary embodiment, utilizing the dimensions previously given and a 11 pound per square inch fuel pressure (acetylene in normal usage) at extremely narrow inlet tube 16. Since the relative position of the glow plug filament or other ignition element 50, the deflector 38 and the nozzle opening 30 would vary somewhat with the pressure of the gaseous fuel and the various dimensions of the nozzle parts, and since the exact positioning is not highly critical, it is merely mentioned that the FIG. 1 and FIG. 2 representations are quite close to scale representations of the exemplary embodiments successfully tested. FIG. 3 shows more clearly the details of parts 30—44 of the nozzle or auxiliary burner.

EXEMPLARY ENTIRE SYSTEM INCORPORATING IGNITER

FIG. 4 is a partially schematic side view of an exemplary complete system including the igniter assembly of the invention. The auxiliary burner or nozzle 10 and its electrical igniting assembly 12 are shown near the middle of the upper part of FIG. 4. These two assemblies may be identical to the one shown and described in detail with reference to FIGS. 1—3, and some of the identical elements thereof are referenced in FIG. 4 with the same numerals. Additional voltage source 68 and switch 70 are shown for energizing coil 50 through leads 64, 66. The exemplary device intended to be ignited by the igniter assembly 10, 12 is indicated near the right-hand side of the figure as a main burner 76'. For purposes of concreteness and ease of explanation, it will be assumed that it is the type of analytical burner utilized in, for example, a atomic absorption spectroscopy in which a gaseous fuel and a gaseous oxidant are supplied (for example, by means of tubes 78, 80 respectively) to a mixing chamber 82 prior to their leaving the top of the burner as from one or more long slots on the upper surface 84 of the burner head 86. If the main burner 76' is specifically adapted for atomic absorption spectroscopy (or flame photometry) means (not shown) would also be provided for supplying a sample (typically as a nebulized liquid solution) into the gases in the mixing chamber. A common technique for accomplishing this is utilizing one of the gases (typically the oxidant) to aspirate a solution of the sample and form a fine spray therefrom by means of a nebulizer, so as to cause sample solution spray or vapor to be mixed with the gases within the mixing chamber 82. An exemplary sampling burner of this type (specifically designed for atomic absorption spectroscopy) is sold by The Perkin-Elmer Corporation of Norwalk, Conn. under part number 303-0110. It is again emphasized that it is merely assumed for purposes of concreteness of explanation that the particular device ignited by flame 74 is a burner of this type; it is obviously not necessary that device 76' even be a laboratory burner, let alone an atomic absorption sampling burner. In the exemplary embodiment it is assumed that the fuel for the main burner supplied at 78 may come from a common fuel tube 88 (by means of tube

90), tube 88 being connected to a suitable supply of compressed gaseous fuel (for example a commercially available compressed cylinder of, say, acetylene gas, followed by a pressure regulator). The same fuel may be supplied by means of branch tube 92 (typically of a smaller diameter) which may be connected directly to the adjacent end 16' of the very small fuel inlet tube 16 to the igniter assembly nozzle 10. The oxidant to the main burner may be supplied to tube 80 at its schematically illustrated open end 80' from any conventional source of compressed oxidant gas, such as a conventional air compressor (or alternatively from a regulated cylinder of suitable compressed oxidant, including air, nitrous oxide or other suitable gas).

In the exemplary automated embodiment of the complete system in FIG. 4, three separate solenoid valves control, respectively: the fuel supply (tubing 90,78) to the main burner as at 94; the fuel supply to the igniter assembly as at 96; and the oxidant to the main burner as at 98. For ease of illustration and explanation, each of these electrically actuated solenoid valves is indicated as having its own energizing source at 104, 106 and 108, respectively; obviously a single source and parallel leads therefrom are more economical and are preferably used in the actual embodiment. Each of the main and igniter fuel solenoids 94,96 are controlled by relay switches 114,116; while solenoid valves 98 is controlled by a mechanical switch 118. All the solenoid valves will be closed except when energized by their respective sources (104, 106, 108) through their respective switches (114, 116, 118). Both of the relay switches 114 and 116 are closed (so as to open the valves 94,96) by a common delay relay solenoid 120, which is energized at the same time that the ignition coil 50 is supplied electrical energy (as by being in series therewith as illustrated) by closing of switch 70. Delay relay solenoid 120 will not cause switches 114, 116 to close until, say, about 2 or 3 seconds after switch 70 has been closed. Whenever switch 116 is closed, not only will solenoid valve 96 be actuated (i.e., opened) but two additionally delay solenoids or relays 122 and 124 will also be supplied energy so as to be actuated after a further delay of, say, a few seconds. Preferably the delay time of solenoid 122 is somewhat greater than the delay time of solenoid 124 (say, 4 and 2 seconds, respectively), so that solenoid 124 will open switch 70 before solenoid 122 reopens switch 116.

A somewhat schematically illustrated mechanical pushbutton linkage 130 may be provided for manually closing the switch 70. Specifically whenever the lower pushbutton end 132 is manually pressed (upwardly in FIG. 4) by the operator, the upper end 134 of the link 130 will mechanically close switch 70'. At the same time an auxiliary linkage 140, the left-hand end of which is connected by pin 136 and loss-motion slot connection 138 to main linkage 130, will be caused to pivot about a fulcrum schematically illustrated at 142 so as to cause the right-hand end 144 to close switch 118. The main vertical portion of linkage 130 is constrained (as by conventional tracks, not shown) to move only a vertical line in FIG. 4.

OPERATION OF ENTIRE SYSTEM

The operation of the exemplary entire system shown in FIG. 4 is as follows. The various switches will initially be in the position shown (i.e., all open) in FIG. 4, so that the three solenoid valves are closed and no gases are flowing to either the igniter or the main burner, and no current is being supplied to igniter coil 50. This is the "off" or "start" condition, and of course no flames will be present in the system. When the operator presses pushbutton 132, switch 70 will be closed so as to start the heating of igniter coil 50 immediately; and simultaneously switch 118 will be closed by auxiliary linkage 140 so as to open solenoid valve 98 to allow gaseous oxidant to enter the mixing chamber through tube 80 (this will also cause aspiration and nebulization of the sample solution in a sampling type burner 76'). Because of the delay nature of the solenoid 120, neither switches 114 nor 116 will close until igniter coil 50 has

had sufficient time (e.g., 2 or 3 seconds) to reach at least the kindling temperature of the fuel utilized. After this delay, solenoid relay 120 will cause closing of both of switches 114 and 116. Closing of switch 116 will of course immediately cause energy source 106 to open the igniter fuel solenoid valve 96 (through a path including the coils of further delay solenoids 122 and 124, namely via leads 123 and 125). Issuance of the gas through the extremely narrow tube 16 to the igniter assembly 10 will be almost instantaneous, as will be the ignition of both the deflected portion of the gas at 72 and therefore the main portion of the gas resulting in flame 74, as previously described. Thus, flame 74 will ignite almost immediately upon actuation of the relay switch 116.

Although relay switch 114 will close simultaneously with switch 116, thereby opening main burner fuel solenoid valve 94 at this same time, there will normally be a short delay (typically a large fraction of a second) before the main burner gas being introduced at tube 78 fills the mixing chamber and starts issuing out of the upper end 84 of the main burner (along with the already flowing oxidant and sample, if any). For this reason no unburnt fuel (e.g., acetylene) should escape to the atmosphere through the upper end 84 of the main burner, since ignition flame 74 will be present before such main burner fuel reaches the top of the main burner. As soon as the fuel of the main burner starts leaving the upper end 84 of the main burner (along with the oxidant that has already been supplied to the main burner, and sample solution if utilized), the main burner flame indicated at 150 will be ignited. After the delay time (e.g., 2 seconds) provided by delay relay or solenoid 124, switch 70 will be opened again (either directly by solenoid 124 or by downward movement of linkage 130,134, either expedient being equally usable in the illustrated exemplary embodiment) so that current will no longer be supplied to igniter coil 50. Because of the loss-motion connection supplied by, for example, slot 138, auxiliary linkage 140 will not be moved even if main linkage 130 is moved downwardly by solenoid 124. Therefore switch 118 remains closed even after delayed solenoid 124 has moved the main linkage 130 back to the position shown in FIG. 4. It may be noted that linkage 130 is provided with sufficient friction (as by a vertical track or other mechanical means) so as to be stable in any position, so as not to move downwardly (and thereby open switch 70) until delayed solenoid 124 moves it downwardly (either directly or through switch 70). Opening of switch 70 of course also deenergizes solenoid 120.

Since delayed solenoid 122 has a longer delay period (say, 4 seconds) than that of solenoid 124, switch 116 will momentarily remain closed so as both to insure energizing of solenoid 124 for sufficient time to cause opening of switch 70, and to allow fuel to be supplied through tube 16 for a further period so as to insure ignition of the main flame 150. After this further delay (of say an additional 2 seconds or so after switch 70 has been opened), delay solenoid 122 will again open switch 116, thereby closing solenoid valve 96 so as to shut off the fuel in tube 16 to the igniter nozzle 10, thereby extinguishing the flame 74. This completes an ignition cycle.

It should be noted that at the end of this ignition cycle, bistable switch 114 will remain closed as will switch 118, so that the main burner fuel and oxidant solenoid valves 94 and 98, respectively, remain open, thereby continuing the supply of oxidant and fuel to the main burner. Thus, all of the elements of FIG. 4 return to their original position except for these two switches, and their controlled solenoid valves. A (say, manually actuated) main burner "off" switch or pushbutton is provided for turning off the main burner at a later time as desired by the operator. As schematically illustrated by mechanical linkage 152 a single switch or pushbutton may be utilized to simultaneously open switches 114 and 118, as long as some type of loss-motion connection is provided to allow switch 118 to be closed (at the beginning of the ignition cycle) without causing closing of switch 114.

SUMMARY

As previously noted concerning the more detailed description of the igniter assemblies 10 and 12 in conjunction with FIGS. 1-3, coil 50 (and in particular its upper part) is not exposed to the relatively intense heat of flame 74 during any part of the operation. In addition to the fact that the deflector 38 allows the coil to be substantially outside of the main part of the igniter flame 74, another advantage accrues from the arrangement utilizing the deflector 38. Because the coil 50 is not in the main part of the gas stream at the time that the fuel is first introduced through tube 16 (i.e., when solenoid valve 96 first opens), the cooling effect on coil 50 of the fuel gas during the moment before it actually ignites is also reduced, insuring that the coil is not cooled by the gas stream below the kindling temperature of the fuel and mixture. Thus, if coil 50 were more or less in the main gas stream, it would either have to be of a relatively high thermal capacity or else raised to a temperature substantially above the kindling temperature of the igniter fuel and air mixture to insure that the blast of cool gas did not immediately cool it below the kindling temperature of the igniter gas mixture. Thus, the deflector allows a fast heating but cooler running igniter element to be used. In the exemplary embodiment of a complete system of FIG. 4, it may be noted that the ignition coil may be electrically deenergized (by solenoid 124 and switch 70) as soon as ignition of flame 74 is assured, thereby limiting to a minimum the amount of time that coil 50 is both being electrically heated and exposed to the (partial) heating effect of flame 74; while the flame 74 can remain on an additional period to insure sufficient time for lighting the main device (e.g., burner 76'). Thus the use of a deflector, as at 38, extends the life of coil 50 not only by insuring that it is out of the main stream of flame 74 after it is lit, but also allowing it to be rapidly heated only just above the ignition temperature of the gases (and in the exemplary system, turned off quite soon thereafter).

Although a single exemplary embodiment of the igniter apparatus (nozzle and heating element assemblies, 10 and 12) and an exemplary manner of utilizing the invention in a complete system have been disclosed, the invention is not limited to any of the details of this exemplary embodiment and exemplary complete system. Rather, the invention is defined solely by the scope of the appended claims.

What is claimed is:

1. An igniter apparatus for producing a flame for igniting a main device, comprising:
means for forming a gaseous stream of mixed fuel and oxidant along a longitudinal axis;
an igniter element positioned immediately adjacent to, but substantially outside of said gaseous stream;
means for sometimes heating said igniter element to a temperature above the kindling temperature of said gaseous stream;
and deflector means comprising a substantially planar surface positioned in a part of said gaseous stream near said igniter element;
said planar surface being at an acute angle to said longitudinal axis of said gaseous stream, and having an effective width as measured in a direction perpendicular to said longitudinal axis of said gaseous stream of only a minor fraction of the width of said gaseous stream, so as to deflect only a minor portion of said gaseous stream toward said igniter element, so as to cause said minor portion to just contact said igniter element in a substantially grazing manner;
whereby when said igniter element is heated, said minor portion of said gaseous stream will be ignited, thereby

causing ignition of the entire gaseous stream, without said igniter element being subsequently exposed to any major part of the resulting flame, so as to avoid undesired substantial heating of said igniter element by said flame.

2. An igniter apparatus according to claim 1, in which: said planar surface is substantially at a 45° angle to said longitudinal axis of said gaseous stream, so as to cause deflection of said minor portion at generally approximately 45° from said longitudinal axis.
3. An igniter apparatus according to claim 1, in which: said igniter element comprises a metallic wire in the form of a coil;
igniter housing means are provided which substantially surround all of said igniter coil except for that part which is most closely adjacent said gaseous stream, whereby almost all of said igniter coil is completely protected from both direct and indirect heating by said resulting flame; and said heating means therefor comprises a source of electrical energy and means for connecting said source to said igniter wire.
4. An igniter apparatus according to claim 3, in which: said igniter coil comprises the heating element of a glow plug.
5. An igniter apparatus according to claim 1, in which: fuel supply control means are provided for turning on and off said gaseous stream;
switch means are provided for turning on and off said heating means for said igniter element;
and operating control means are provided for causing said switch means to turn on said igniter element before said fuel supply means is turned on;
whereby said igniter element reaches the kindling temperature of said gaseous stream before said fuel supply is turned on.
6. An igniter apparatus according to claim 5, in which: said means for forming said gaseous stream comprises means for receiving a gaseous fuel and for sucking ambient air into the gaseous fuel stream;
whereby said fuel supply control means also effectively turns on the gaseous oxidant, when it turns on the fuel.
7. An igniter apparatus according to claim 6, in which: said fuel supply control means comprises a valve;
said operating control means comprises a first delay means, operated by said switch means;
and said first delay means is operatively connected to open said valve so as to turn on said fuel only after the delay provided by said first delay means.
8. An igniter apparatus according to claim 7, in which: said first delay means also is operatively connected to the main device to place it in operating condition when said igniter fuel supply is turned on;
whereby upon ignition of said igniter flame, said main device is readied to be ignited thereby.
9. An igniter apparatus according to claim 7, in which: said first delay means also is operatively connected to actuate a second delay means;
and said second delay means is operatively connected to said igniter switch means to turn off said igniter element after a further delay to avoid unnecessary heating thereof by said heating means.
10. An igniter apparatus according to claim 7, in which: said first delay means also is operatively connected to actuate a third delay means;
and said third delay means is operatively connected to turn off said fuel supply valve after a substantial further delay, so as to automatically turn off said igniter assembly flame after it has had ample time to ignite said main device.
